UNITED STATES PATENT OFFICE.

CHRISTOPHER O. COLE, OF BELLINGHAM, WASHINGTON.

HAULING APPARATUS.

1,071,882.

Specification of Letters Patent. Patented Sept. 2, 1913.

Application filed November 12, 1912. Serial No. 730,980.

To all whom it may concern:

Be it known that I, CHRISTOPHER O. COLE, a native-born citizen of the United States, and resident of Bellingham, in the county of Whatcom and State of Washington, have invented certain new and useful Improvements in Hauling Apparatus, of which the following is a specification.

My invention has particular reference to apparatus of the above type wherein the mechanism, in transmitting the energy imparted to the prime mover to the load moved thereby, performs the work of overcoming the resistance to the movement of the load by pulling a length of steel wire rope, or cable, in and winding it up while the end of the cable, not engaging the hauling apparatus, is fastened onto the load moved.

The hauling apparatuses of the common known types perform the functions required, in the art of moving a load by pulling a length of cable in and winding it up while the end of the cable, not engaging the haul, is fastened onto the load moved, by either employing two means for applying power to the cable, one for pulling the cable in and one for winding it up, or else the one means employed for applying power to the cable winds the cable in on itself. Thus it is obvious that in the operation of these hauls there will either be an undesirable waste of power in the mechanism employed for driving the two means employed for applying power to the cable, incident to their keeping in step with each other while pulling on the same cable, or else there will be an undesirable variation in the relative velocity of the periphery, at the point of action of the energizing forces on the rotatable member of the prime mover, and the velocity of the load moved thereby. This variation in the relative velocity of the periphery, at the point of action of the energizing forces on the rotatable member of the prime mover, and the velocity of the load moved, being caused by the varying diameter of the arc of application of power of the means employed for pulling the cable in and winding it up, incident to its filling up with cable.

Primarily the object of my invention is the provision of means which are adapted to transmuting electrical energy into mechanical motion that is capable of doing the work of overcoming the resistance to the movement of a load by pulling a length of

cable in and winding it up while the end of the cable not engaging the mechanism is fastened onto the load moved. And, the successful and efficient accomplishing of the above object requires, preferably, the elimination of the waste of power referred to above as being prevalent in the operation of one class of hauls of common known type, and, it necessarily requires the elimination of a desired greater amount of the variation in the relative velocity of the periphery, at the point of action of the energizing forces on the rotatable member of the prime mover, and the velocity of the load moved, referred to as being prevalent in the operation of the other class of hauls of common known type.

My invention relates to new and more efficient means which, while capable of performing the service required in the art of moving a load by pulling a length of cable in and winding it up while the end of the cable not engaging the haul is fastened onto the load moved, are, as hereinafter more fully described and set forth, capable of performing the functions required in the service of the art of eliminating or creating of any desired amount of variation in the relative velocity of the periphery, at the point of action of the energizing forces on the rotatable member of the prime mover, and the velocity of the load moved thereby. This eliminating or creating, as desired, of variation in the relative velocity, as mentioned above, being effected in hauling apparatuses wherein the diameter of the arc of application of power, to the cable employed for connecting the haul with the load moved, is variable, incident to the varying diameter of the means employed for winding the cable up, as it fills up, with or empties of cable.

Incident to the accomplishing of the prime object of my invention and further incident to the performing of the functions required in the service of the art mentioned above, is the still more important and principal object of my invention which is the provision of means which are capable of moving a load by pulling a length of cable in and winding it up while the end of the cable not engaging the haul is fastened onto the load moved; and, wherein the variation, in the relative velocity of the periphery at the point of action of the energizing forces on the rotatable member of the prime mover

and the velocity of the load moved thereby, is reduced to any desired minimum variation.

To attain the objects referred to above it is obvious that the power of the prime mover must be delivered through two independent mechanical connections to two or more points on the cable. One of the mechanical connections being provided to have one of its members connect with the loaded cable and pull it in; while the other mechanical connection is provided with a member which winds the cable, thus pulled in by the first named member, up; and, in applying its power to the cable, creates a pull thereon keeping it tight and preventing it from slipping on the means employed for pulling the cable in. To provide driving means that will operate these two independent mechanical connections, driving their respective members that connect with the cable, at the varying speeds required incident to one member pulling the cable in and the other member winding the same cable up, without using a slipping clutch mechanism or two independent prime movers, I propose to use an electric motor, of any common or well known type; which, drives a differential gear of the common and well known type such as are in general use for driving axles on tractors and automobiles. The two shafts of this differential being connected up through two different sets of gear mechanisms to the two independent means for connecting with the one length of cable to be used by the haul for moving the load.

My invention performs the service, hereinbefore described, as required of it, by its ability to distribute the mechanical power of the prime mover through the differential gear and thence through two different sets of gear mechanisms to two different drums or sets of drums; which, drums, constitute the two independent mechanical connections capable of applying power to a length of cable by one of them pulling the cable in and the other one winding it up. And the variation in leverage that would ordinarily be incident to a mechanism while pulling a length of cable in and winding it up, and through which variable leverage the prime mover must move the load, is eliminated in part or in whole, as desired and constricted in my invention, by the gear ratios of the mechanisms transmitting the mechanical motion, received of the prime mover, to the cable at the two independent points; and, by the compensating action of the cable passing from the mechanical means employed for pulling it in to the mechanical means employed for winding the cable up.

The gear ratios referred to above may be constructed in the various different hauls as desired and arranged to overcome any desired amount of the variation in the leverage

incident to the increasing diameter of the mechanical means employed for winding the cable up, as it fills up with cable. For instance: the gear ratios, between the mechanical means employed for winding the cable up and the shaft of the differential which drives it, may be made such that a reduction of 25 R. P. M. in the revolutions of the means employed for winding the cable up, incident to its keeping in step with the movements of the means employed for pulling the cable in and to its increased diameter at the point of application of power as it fills up with cable, will cause a reduction of 20 R. P. M. in the revolutions of the differential shaft driving it. This reduction of 20 R. P. M., in the revolutions of the differential shaft that drives the means employed for winding the cable up, will in turn, by reason of the speed of the main gear of the differential having to remain very nearly constant in order for the motor driving it to keep in step with the electrical current energizing it, cause a corresponding increase of 20 R. P. M. in the revolutions of the other shaft of the differential. This latter differential shaft is the one that drives the mechanical means employed for pulling the cable in. And the gear ratio, between it and the means employed for pulling the cable in, may be made such that the increase of 20 R. P. M. in the revolutions of the differential shaft will only cause the means employed for pulling the cable in to make an increase of 2 R. P. M. And this increase of 2 R. P. M. in the revolutions of the mechanical means employed for pulling the cable in, will cause that member to pull more cable in and deliver it back to the means employed for winding the cable up. Hence, the member employed for winding the cable up, will not slow down and make the relative reduction in its R. P. M. that the increased diameter, incident to its filling up with cable, would tend to require. Thus the pulling in and winding up of sufficient length of cable to make a variation of 25 R. P. M. in the revolutions of the member employed for winding the cable up, will make a variation of less than 2 R. P. M. in the revolutions of the member, employed for pulling the cable in, where most of the power of the prime mover is applied to the cable for moving the load.

Briefly the elements of my invention are: a prime mover; a differential gear, of the type in common use for driving axles on automobiles and tractors; two independent mechanical means, for connecting with a length of cable; and a length of cable; in combination with a length of said cable for connecting the hauling apparatus with the load to be moved.

Specifically, I propose to use, in my invention, as a mechanical connection for ap-

plying most of the power of the prime mover to pulling the cable in, two simultaneously driven drums having annular grooves on their surfaces provided to receive several folds of the cable. These two simultaneously rotating haul-drums are shown by reference numerals 2 and 3 Figs. 1 and 2, on the accompanying drawings which form a part of these specifications. 10 These two sheets of drawings present the three views,—a top plan view, and a side elevation with parts broken away,—and a detail view of the differential gearing showing its three principal elements and fragments of the shafts 24 and 30, showing a construction embodying the principles of my invention; and, are submitted to show the various elements of my invention, and their relation to each other, together with 20 their connecting members.

The two simultaneously rotating haul-drums 2 and 3 are loosely mounted on their respective shafts 5. These shafts 5 are journaled on suitable bearings which are mounted on the frame 4; and, are provided with worm gears 6 which mesh with drive worm pinions 7. Each of these haul-drums 2 and 3 has releasable driving connection with its shaft 5 through the medium of respective 25 friction clutches 8, 9 and 8', 9' of the common cone,—wood to iron,—type. These drums 2 and 3 are arranged for lateral motion on their shafts; and, are provided with air operated piston clutch-controls 10 which 30 set the drums up bringing the clutch members 8, 9 and 8', 9' into engagement with each other against the required clutch opening springs. These two simultaneously rotating haul-drums 2 and 3 have the cable 15 35 pass back and forth between and take over their grooved surfaces, thus making a number of folds encircling them, as shown; and, apply the power of their rotating surfaces to the cable 15 by their continual and successive frictional connection at the plurality of arcs of contact therewith where the cable 15 takes over them. Thus these two haul-drums 2 and 3 pull the loaded cable 15 in; and, deliver it back to the winding-drum at the rear of the haul, (see No. 40 1, Figs. 1 and 2.) where it is wound up.

The winding drum 1 is provided to act as a spool tender to the haul-drums 2 and 3; and, it winds the cable 15 in on itself, delivering only a small part of the power of the prime mover to the cable 15 through positive mechanical and frictional continuous and successive connection therewith. This winding-drum 1 is designed to create sufficient pull on the cable 15, while winding it up, to maintain the required tension thereon to keep the cable 15 from slipping in the grooves on the haul-drums 2 and 3 while the haul-drums 2 and 3 are pulling the cable 15 in and moving the load fastened thereto.

Reference numerals 11 and 12 indicate drive and driven members of a friction clutch of the common cone,—wood to iron,—type. This clutch constitutes a releasable driving connection between the winding-drum 1 and its shaft 16; and, is under control of the operator through a common air operated piston clutch-control 17.

The shaft 16 mounting the winding-drum 1 is suitably journaled in bearings that are mounted on one section of the frame 4 and, is driven by bevel gears 13 and 14. The gear 14 being fixed on one end portion of the shaft 24 of the differential 25 through which the winding-drum 1 receives its part of the power from the driving motor 35.

In the distribution of the power of the motor 35 to the cable 15 the mechanical motion of the motor 35 is transmitted through a pinion 33 that is fastened onto the armature shaft 34 engaging and driving the main gear 26 of the differential 25. From thence, the power is distributed by the differential and delivered through two different sets of gear mechanisms to the two independent means of applying power to the cable 15. One set of gear mechanism transmitting the greater part of the power to the haul-drums 2 and 3 for pulling the loaded cable 15 in, while the remainder of the power is delivered through another set of gear mechanism to the winding-drum 1 for winding the cable, pulled in by the haul-drums 2 and 3, up. Thus the differential 25 in distributing the power, it receives of the motor 35, divides it and delivers the desired amount, according to the gear ratios of the respective mechanisms, to its respective shafts 24 and 30. These shafts 24 and 30 constitute respectively the drive shafts for the winding-drum 1 and the haul-drums 2 and 3. The shaft 30 receiving power from the differential 25 delivers it through the worm gears 6 and 7, shafts 5, clutches 8, 9 and 8', 9', simultaneously to the haul-drums 2 and 3, while the shaft 24 is delivering the power it receives from the differential through pinions 14, 13, shaft 16, and clutch 11, 12, to the winding-drum 1. However it is obvious that neither one of the shafts 24 or 30 and its respective driven mechanism is capable of delivering power or doing the work of overcoming the resistance to the movement of a load unless the other shaft is simultaneously doing work or is held from rotating by a brake. Accordingly, as it will be desirable to use but one of these shafts for transmitting power, a brake 36, operated by a piston 37, is provided to hold the shaft 24 and its driven mechanism from rotating so that all the power of the prime mover will be delivered through the shaft 30, worm gears 31, 32, shaft 27, clutch 44, 45, to drive the haul-back cable-drum 46. This drum 46 being provided to wind the haulback-cable in on

itself; and, to pull the main cable 15 out to the works.

5 An additional drum 40 is mounted on one end of the shaft 5 that mounts the haul-drum 3. This drum 40 and its cable 41 are provided to move additional loads about the works simultaneously with the operations of the other working members of the haul.

10 Drums 40 and 46 are each provided respectively with common cone, wood to iron, friction clutches 42, 43, and 44, 45, which are operated by the air operated piston clutch-controls 18 and 19.

15 The several clutches 8, 9, -8', 9', -11, 12, -42, 43, and 44, 45, which constitute the releasable driving connections between the several drums 1, -2 and 3, -40, - and 46, and their respective shafts, are controlled by the operator through controlling valves 20 which are provided to admit air from the air storage tank 22 to the piston clutch-controls on the respective drums.

20 Reference numeral 21 indicates an automatic motor driven air compressor set provided to supply the air required for operating the piston clutch-controls, the brake piston 37, and the signal whistle used in connection with the operations of the machine.

25 In operating the haulback drum 46 or the extra drum 40 air is admitted from the tank 22 to the cylinder 37 of the brake 36 setting it and holding the differential shaft 30 to the drum shafts 5 and 27. Then, upon admitting air to the piston clutch-controls 18 and 19, as desired the engagement of the respective clutch will be effected and the desired rotation of the respective drum 40 attained.

30 In connection with drums 40 and 46, are provided brakes 28 and 29 respectively whereby the cables 41 and 47 can be kept under proper tension while being "run out." 45 These brakes 28 and 29 preferably consisting of bands connected with foot operative levers, as 38 and 39, and engaging over annular flange extensions of the drums, as clearly shown.

50 Reference numeral 23 indicates an electric current controller, of any common or well known type, provided to control the current supplied to the motor 35; and, is arranged to be conveniently located near the operative levers 20 and brake levers 38 and 39.

55 In the operation of the several members combining to form the elements of my invention, the length of cable 15 that passes back from the haul-drums 2 and 3 to the winding-drum 1 will keep the peripheral speeds of the arcs of application of power, of the two independent members connecting with and applying power to the cable 15, drums 1, and 2 and 3, in step at all times.

However, as the diameter of the arc of application of power to the cable 15 by the winding-drum 1 varies as the drum 1 fills up with or is emptied of cable, this constant peripheral speed, of the arc of application of power by the winding-drum 1, incident to its keeping in step with the haul-drums 2 and 3 whose arcs of application of power do not vary in diameter, will cause a variation in the number of R. P. M. that the winding-drum 1 will make in winding a relative length of cable 15 up. And this variation in the R. P. M. of the winding-drum 1 causes a relative variation in the R. P. M. of the shaft 24 of the differential 80 from which it receives power. The amount of this relative variation, in the R. P. M. of the winding-drum 1 and the R. P. M. of the shaft 24 through which it receives power, being fixed by the gear ratio of the connecting gears. Then further the variation, in the R. P. M. of the shaft 24, will cause a corresponding inverse variation in the R. P. M. of the other shaft 30 of the differential 25. This, in turn, will cause a relative variation in the R. P. M. of the haul-drums 2 and 3, the amount of which relative variation in the R. P. M. of the haul-drums 2 and 3 and the R. P. M. of their driving shaft 30, being fixed by the gear ratios of the mechanism through which the haul-drums 2 and 3 receive power. And this variation, in the R. P. M. of the haul-drums 2 and 3 acting back through the cable 15 that they deliver to the winding-drum 1, to be wound up, will cause a variation in the R. P. M. of the winding-drum 1 inverse to and counteracting some of the variation in the R. P. M. of the winding-drum 1 incident to the varying diameter of its arc of application of power to the cable 15 as the cable 15 is wound on or off the winding-drum 1.

60 It is obvious from the foregoing that as the winding-drum 1 fills up with cable 15 it will make fewer R. P. M. This, in turn, will cause a reduction in the R. P. M. of its drive shaft 24. And owing to the R. P. M. of the main gear 26 of the differential 25 having to remain very nearly constant, in order for the motor 35 to keep in step with the electrical current energizing it, the reduction, in the R. P. M. of the shaft 24 will cause a corresponding increase in the R. P. M. of the other shaft 30 of the differential 25; this in turn will cause the haul-drums 2 and 3 to pull more cable in and deliver it back to the winding-drum 1 to be wound up. And therefore the winding-drum 1 will not slow down quite as much as the increased diameter, caused by its winding the cable 15 up, would tend to make. Thus it is further obvious, from what has just been shown, that as the winding-drum 1 fills up with cable 15 it will 130

slow down and make relatively fewer R. P. M. as compared to the R. P. M. of the energized rotatable member of the motor 35; and this, in turn, will cause the haul-drums 2 and 3 to speed up and make relatively more R. P. M. as compared to the R. P. M. of the energized member of the motor 35. Thus the haul-drums 2 and 3, in making the increased R. P. M. incident to the winding-drum 1 filling up with cable 15, will pull the load at a relatively faster speed as compared to the velocity of the periphery of the rotatable member of the prime mover 35 at the point of action of the energizing electrical forces that cause the armature of the motor to rotate with respect to the field, thus causing a slight variation in the leverage through which the prime mover pulls the load on the cable 15.

20 However it will be seen that the gear ratios, between the winding-drum 1 and its drive shaft 24, and between the haul-drums 2 and 3 and their drive shaft 30, may be made such that the relative variation, in the R. P. M. of the haul-drums 2 and 3 as compared to the R. P. M. of the energized rotatable member of the motor 35, will be very slight; thus enabling the haul to deliver the power of the prime mover to the cable 15, for moving the load, at very nearly the same leverage throughout the entire operation of the haul while pulling, the entire length of cable used for moving the load, in and winding it up.

35 The above is one of the salient features of my invention and by using different sized gears, producing different gear ratios between the rotatable member of the prime mover and the haul-drums 2 and 3 and the winding-drum 1, in constructing the different hauls, any desired variation, in the relative velocity of the periphery, at the point of action of the energizing forces on the rotatable member of the prime mover, and the velocity of the load moved thereby, may be obtained.

40 While I have herein referred to my invention as being a hauling apparatus, it is obvious that it is equally well adaptable for hoisting or for moving other loads whenever a cable is used to connect the mechanism of the prime mover with the load moved. And while the construction shown in these specifications of my invention present a mechanism wherein the several members, required to perform the several functions in the service thereof, are presented and their relation to each other shown; it is obvious that various changes may be 45 made with respect to the structural parts, without departing from the spirit of my invention as defined in my annexed claims.

46 Thus, having clearly designated the object and purpose of my invention and having shown and described a construction, em-

bodying the principles thereof, wherein it is clearly shown that the several members comprising the elements of my invention, not only perform the functions required in the service of the art herewith presented, which service is the eliminating of the desired amount of the variation in the relative velocity of the periphery, at the point of action of the energizing forces on the rotatable member of the prime mover, and the velocity of the load moved thereby; and which service is performed by the gear ratios in the mechanism and the compensating action of the cable passing from one member to the other, (such as the cable 15 passing back from the haul-drums 2 and 3 to the winding-drum 1); but that they are also capable of performing the functions required, in the service of the art of pulling a length of cable in and winding it up, in a new and more efficient manner.

47 Therefore, what I claim as new and desire to secure by Letters Patent of the United States of America, is:

1. In a hauling apparatus of the character described, the combination of a prime mover, a differential gearing comprising a driving element and a pair of driven elements, driving connections between said prime mover and said driving element, two cable-hauling devices, individual driving connections between each of said driven elements and a corresponding one of said cable-hauling devices, and a cable arranged in successional operative connection with said cable-hauling devices.

2. In a hauling apparatus of the character described, the combination of a prime mover, a differential gearing comprising a driving element and a pair of driven elements, driving connections between said prime mover and said driving element, two cable-hauling devices, individual releasable driving connections between each of said driven elements and a corresponding one of said cable-hauling devices, and a cable arranged in successional operative connection with said cable-hauling devices.

3. In a hauling apparatus of the character described, the combination of a prime mover, a differential gearing comprising a driving element and a pair of driven elements, driving connections between said prime mover and said driving element, two cable-hauling devices, individual positive fixed driving connections between each of said driven elements and a corresponding one of said cable-hauling devices, and a cable arranged in successional operative connection with said cable-hauling devices.

4. In a hauling apparatus of the character described, the combination of a prime mover, a differential gearing comprising a driving element and a pair of driven elements, a brake means for one of said driven

elements, driving connections between said prime mover and said driving element, two cable-hauling devices, individual driving connections between each of said driven elements and a corresponding one of said cable-hauling devices, and a cable arranged in successional operative connection with said cable-hauling devices.

5. In a hauling apparatus of the character described, the combination of a prime mover, a differential gearing comprising a driving element and a pair of driven elements, a brake means for one of said driven elements, driving connections between said prime mover and said driving element, two cable-hauling devices, individual releasable driving connections between each of said driven elements and a corresponding one of said cable-hauling devices, and a cable arranged in successional operative connection with said cable-hauling devices.

6. In a hauling apparatus of the character described, the combination of a prime mover, a differential gearing comprising a driving element and a pair of driven elements, a brake means for one of said driven elements, driving connections between said prime mover and said driving element, two cable-hauling devices, individual positive

fixed driving connections between each of 30 said driven elements and a corresponding one of said cable-hauling devices, and a cable arranged in successional operative connection with said cable-hauling devices.

7. In a hauling apparatus of the character described, the combination of a prime mover, a differential gearing comprising a driving element and a pair of driven elements, brake means for one of said driven elements, driving connections between said prime mover and said driving element, two cable-hauling devices, positive fixed driving connections between one of said driven elements and a corresponding one of said cable-hauling devices, releasable driving connections between the other of said driven elements and a corresponding one of said cable-hauling devices, and a cable arranged in successional operative connection with said cable-hauling devices. 50
